UNITED STATES PATENT OFFICE

JOSEPH J. BAUMAN, OF CHICAGO, ILLINOIS

CLOSURE CHECK

Application filed May 28, 1928. Serial No. 281,041.

My invention relates to closure checks, and more particularly to a cushion bumper having a maximum effective range of displacement wherein the initial yielding resistance 5 will be materially augmented as the compression progresses.

While the present form of cushion bumper has been especially designed for arresting the closing movement of automobile doors and 10 the like, it may also be applied to a wide range of other uses as for arresting doors of other structures, sliding drawers, or as stops for other moving bodies. Therefore, while the invention will be described in its relation to 15 automobile doors it is to be understood that it is not limited to such use.

In the present invention there is contemplated a body of rubber or a rubber substitute, having a resilient characteristic to be 20 mounted in a socket or otherwise suitably supported, with one end of such body projecting a relatively greater distance beyond the mounting than such bumpers or checks ordinarily protrude. This projecting face of 25 the bumper or check is preferably of convex arcuate form. The resilient body is provided with a hole therein, preferably of segmental shape, the arcuate side of which is disposed in substantially concentric spaced relation 30 with the convex contact face of the bumper body. Such hole allows sufficient space for the distortion of the projecting portion of the bumper, which portion yields with minimum 35 resistance until such hole is completely closed, whereupon further compression is resisted conjointly by such initially compressed portion and the main body of the bumper. In its preferred form this initially compressed projecting contact portion of the 40 bumper body is of substantially arch shape, the ends of which are integrally united with the main body.

The primary function of such check or bumper is not only to cushion the impingement of the door when closing, but also to exert a constant outward pressure against this door when closed to automatically take up play between the door latch and keeper plate to prevent rattling or clatter.

50 Rubber door bumpers are now commonly

used for this purpose but such bumpers are capable of only limited displacement or compression and therefore cannot be permitted to protrude far beyond their support. When the material of such bumper as ordinarily 55 constructed loses a portion of its resiliency it fails to exert sufficient outward pressure against the door and consequently the door is permitted to rattle or vibrate causing great 60 annoyance.

The novel form of check or bumper forming the subject matter hereof is capable of a much greater effective displacement or distortion without necessitating additional door pressure or affording great resistance. It 65 protrudes a much greater distance beyond its support and hence it is enabled to follow the door through a greater range and control its vibratory movement through a greater extent. The cutout or hole, which is preferably 70 though not necessarily of segmental form, affords space into which the excess material may be compressed and permits the setting up of a bending stress in such protruding portion rather than a direct compressive strain. 75 When the protruding portion of the cushion bumper has been initially compressed sufficiently to eliminate the curved opening it will then be substantially equivalent to the ordinary solid bumper and capable of still further compression against the resistance of the entire body throughout as great range as 80 the ordinary bumper possesses.

The object of the invention is to simplify 85 the structure, as well as the means and mode of operation of cushion bumpers, whereby they will not only be cheapened in construction, but will be more efficient in use, positive in operation, uniform in action, possess a greater range of expansion and compression 90 and unlikely to get out of repair.

A further object of the invention is to provide a resilient cushion or check having an increased range of expansion and compression, the initial compression of which will be 95 against a yielding resistance less than that of the subsequent and final compression, and wherein the initial effect will be a bending strain followed by bodily compression, affording an effective resistance through all the 100

intermediate stages of a wide range of action. A further object of the invention is to provide a cushion bumper having therein an opening into which the material may be initially displaced to compensate for the increased range of distention of such bumper.

5 A further object of the invention is to provide a cushion bumper having an increased degree of resiliency, a greater life and durability.

10 With the above primary and other incidental objects in view, as will more fully appear in the specification, the invention consists of the features of construction, the parts and combinations thereof, and the mode of operation, or their equivalents, as hereinafter described and set forth in the claims.

15 Referring to the accompanying drawings, wherein is shown the preferred, but obviously not necessarily the only form of embodiment of the invention, Fig. 1 is a perspective view of the cushion bumper or check forming the subject matter hereof. Fig. 2 is a similar view of such cushion bumper or check under compression. Fig. 3 is a detail perspective view of the jamb of an automobile door showing two of the bumper cushions herein described embodied therein. Fig. 4 is a sectional plan view of an automobile door 20 and its jamb showing the relation of the cushion bumper, such section being taken on line 4—4 of Fig. 3. Fig. 5 illustrates three cushion bumpers under different degrees of compression showing the relative degrees of compression under different conditions indicated by spaced lines common to the several views.

25 Like parts are indicated by similar characters of reference throughout the several views.

30 In the accompanying drawings, 1 indicates the jamb of an automobile body door opening which is usually formed with a rabbet 2. Insert in mortises or sockets formed in jamb 1 are two cushion bumpers comprising bodies 35 of rubber or other resilient material 3, the inner ends of which are preferably, though not necessarily of substantially semi-circular form abutting upon the inner surface of the socket or mortise of the jamb within which the bumper is seated. The bumper is confined within such socket or mortise throughout its greater extent with its contact face 4 projecting relatively a considerable distance within the rabbet of the door jamb. The 40 contact face 4 of the bumper which is one of the marginal end surfaces is preferably, though not necessarily, of convex arcuate form. Located within the body 3 of the bumper in spaced relation with the convex contact face 4 and preferably concentric therewith is a segmental opening 5. There is thus formed at the outer or effective end of the bumper body a substantially arch shaped portion 6, the ends of which arch are 45 integrally united with the main body of

the bumper while the medial portion thereof is separated from such main body by the interposed segmental opening 5.

50 The usual automobile door construction is rabbeted to agree with the rabbet of the jamb 1 as indicated at 7 in Fig. 4. Upon the closing of the door the shoulder of the rabbet 7 contacts the convex face 4 of the bumper body, and as the door continues its closure movement, the bumper body is compressed. The initial compression effects in a bending strain of the arch section 6 of the bumper body straightening or flattening this arched portion until the opening 5 is completely eliminated as indicated at 8 in Fig. 2. Thereupon the cushion bumper embodies the characteristics of a solid rubber bumper as ordinarily employed and is yet capable of the ordinary degree of compression of such bumper. As the door is pressed to its final "home" position, such movement is effected against the conjoint resistance of the initially compressed arched portion 6 and the main portion or body 3. Thus the shape and arrangement of the body gives it an extended range of expansion and contraction in which the contact surface 5 of the bumper is enabled to follow the movement of the door through a greater degree of movement and hence exert its expansive pressure thereon to more effectively prevent rattling or vibration.

55 This range of compressive action is comparatively illustrated in Fig. 5 wherein a group of cushion bumpers is shown in progressive stages of compression. The initial bumper I is shown fully expanded. The second bumper body of the group II is shown subjected to the initial compression during which the arched portion 6 has been distorted or flattened to eliminate the opening 5, the displacement of the contact face 5 being indicated by the spacing of the lines A—B. In other words the position II shows in comparison with the bumper I the range of additional expansion and contraction afforded by the present construction over that of the ordinary solid rubber bumper which will quite agree with the bumper body shown in its compressed form II in Fig. 5. However, in this condition the present bumper is still capable of further compression through the normal range of an ordinary solid rubber bumper until it assumes the final compressed form shown at III, Fig. 5. The variation or further degree of compression is illustrated by the relative position of the line B—C which spacing also indicates the ordinary degree of displacement of the usual solid rubber bumper. The bumper body 3 is provided with a countersunk hole 9 to receive an attachment screw for fixedly securing the bumper in its position within the receiving mortise or socket of the door jamb.

60 While the invention has been described in its relation to a door jamb it is to be under-

stood that it is not limited to such application, but may be utilized as a stop member for moving bodies of other character.

The present bumper construction possesses 5 a greater effective range of compression by which it is enabled to acquire under compression sufficient tension or yielding resistance to prevent a door from rattling, even though the bumper may not necessarily be compressed 10 to its extreme limit. That is to say the present bumper will compensate for lost motion and inaccuracy of fitting of the door over a much greater range than the usual bumper.

The provision of the arched outer portion 15 afforded by the clearance opening causes a bending stress to be set up under which the arch is flattened in addition to a compression strain, by the closing of the door upon the bumper. While the bumper is capable of a 20 more extended degree of distortion it is effective in all its intermediate stages of compression, and hence its range of effective operation is materially increased.

From the above description it will be apparent 25 that there is thus provided a construction of the character described, possessing the particular features of advantage before enumerated as desirable, but which obviously is susceptible of modification in its 30 form, proportions and arrangement of parts without departing from the principle involved or sacrificing any of its advantages.

While in order to comply with the statute 35 the invention is described in language more or less specific as to structural features, it is to be understood that the invention is not limited to the specific details shown, but that the means and construction herein disclosed comprise the preferred form of several modes 40 of putting the invention into effect, and the invention is therefore claimed in any of its forms or modifications within the legitimate and valid scope of the appended claims.

Having thus described my invention, I 45 claim:

1. A cushion bumper including a substantially flat main body of resilient material to be seated within a recess in a door jamb and an integral arch shaped extension thereof 50 normally projecting beyond the jamb, the ends of which are connected to the main body with the intermediate portion thereof spaced therefrom, said arched portion affording the contact portion and receiving the initial pressure whereby said arched portion is collapsed 55 into contact with the main portion, the further pressure being resisted conjointly by said parts.

2. A cushion bumper comprising a resilient 60 main portion to be seated within a receiving socket in a door jamb and a resilient supplemental portion normally projecting beyond the limit of the receiving socket, the crown of which is spaced from the main portion, said 65 bumper affording progressively increasing

yielding resistance to pressure wherein the supplemental portion is subjected to contact pressure tending to initially distort the arcuate portion into contact with the main portion, the subsequent pressure being yieldingly resisted conjointly by the main and supplemental portions. 70

3. A cushion bumper adapted to afford progressively increasing yielding resistance to pressure including a substantially flat body of resilient material subjected to longitudinal thrust compression in its general plane, said body having a hole therein in proximity to the terminal impact surface of the body, the material intermediate said hole and the impact surface being adapted to yield under compression until said hole is substantially closed by the distortion of the body and such intermediate portion in contact with the main body beyond the hole, the further compression being yieldingly resisted by the said intermediate portion in conjunction with the main body. 75 80 85

4. In a construction of the character described, a block of resilient material, a supporting structure having a socket therein in which the block of resilient material is confined with one marginal face projecting beyond the support, such projecting portion being of convex shape, the body having a hole in that portion confined within the socket affording room for the displacement under compression of the greater portion of the body projecting beyond the support. 90 95 100

5. A bumper cushion including a block of resilient material, one end of which is of substantially semi-circular contour, the opposite end of which is of arcuate form upon a greater radius, and a segmental hole in said body having its straight side disposed toward the semi-circular end of the block and its arcuate side disposed toward and substantially concentric with the opposite end of the block. 105

6. In a construction wherein a rabbeted door jamb is provided with a socket open on two sides for the reception of a buffer block, a resilient buffer block fixedly held in said socket and having an integral arcuate terminal portion projecting beyond the socket for engagement with a door, said arcuate terminal portion being partially separated from the main body of the buffer block by an intermediate space which affords clearance for the initial displacement of the arcuate terminal portion into contact with the main body after which the entire body is subject to compression. 115 120

In testimony whereof, I have hereunto set my hand this 22nd day of May A. D. 1928.

JOSEPH J. BAUMAN. 125
